UNITED STATES PATENT OFFICE.

OSCAR L. SCALBOM, OF GLENVIEW, ILLINOIS.

SAFETY-LATCH FOR MACHINE-CONTROLLING DEVICES.

1,201,355.

Specification of Letters Patent. Patented Oct. 17, 1916.

Application filed November 13, 1913. Serial No. 800,891.

To all whom it may concern:

Be it known that I, OSCAR L. SCALBOM, a citizen of the United States, and a resident of Glenview, in the county of Cook and 5 State of Illinois, have invented certain new and useful Improvements in Safety-Latches for Machine-Controlling Devices, of which the following is a specification.

My present invention relates in general to 10 safety latches and more particularly to automatically acting latches for controlling the operating of machines, and has special reference to the provision of a device of the character referred to adapted for use on 15 power driven machines repeatedly performing the same operation.

The principal objects of my present invention are, broadly stated, first: the provision of a device of the character referred 20 to in the operation of machines in which the same is embodied the simultaneous use of both of the hands of the operator of the machine is required; and, second: the provision of improved means whereby but a single cycle of operation of the machine is possible until such time as the parts are restored to their original position by the operator; the provision of manually operated 25 latch mechanisms for machines characterized by the requirement that one hand of the operator must be continuously employed in holding the latch mechanism out of engagement, and the other hand thereof continuously employed, first, in throwing and 30 then in holding the operating mechanism into engagement for and during the period of time a cycle of operation of the machine is begun and carried on and either concurrently therewith or independently thereof, 35 automatically actuated mechanism permitting but a single complete operation of the machine until such mechanism is intentionally reset; together with such further and additional objects as may hereinafter appear.

While devices embodying my present improvements have a large field of utility and by extension and slight modification to suit the character of machines wherewith they are used, are applicable to a wide range of 45 semi-automatic and other machine tools and machines, I have found them particularly useful in connection with reciprocating punch presses, and therefore for purposes of illustration proceed to show and describe 50

my present improvements as arranged for 55 use in connection with a punch press of a type well known in the art.

As is well known to those who are skilled in the art to which my invention pertains, a large proportion of industrial accidents 60 which take place in machine shops are due to the fact that operators of punch presses and other machines whereby the performance of a given operation is repeated many hundreds of times daily become so habituated to the use of the machines that they become careless and fail to take proper precautions, not only in properly placing the material to be operated upon, but especially in keeping their hands and more particularly their fingers out of the line of movement of the punch.

My present invention has, therefore, a two-fold aspect, first: to require the use of both of the hands of the operative in securing the operation of the machine in order to keep them clear of the moving parts of the machine, and, second: in the present case, to permit but a single stroke of the ram carrying the punch, prior to such time 75 as both hands of the operative are moved from the machine after the completion of the operation thereof and the machine restored intentionally to its original position and ready for another manually actuated 80 operation, thus securing not only safety to the operator but also a saving from loss or damage of the material operated upon.

In accomplishing the foregoing and such other objects as will hereinafter be disclosed 90 and gaining certain additional advantages to be below specifically pointed out, I have provided the construction illustrated in the accompanying drawings, wherein—

Figure 1 is a side elevational view of a 95 reciprocating punch press having a safety device for the clutch operating rod thereof, embodying my present improvements, in a preferred form, applied thereto, the parts being shown in position ready for the beginning of a forming operation; Figs. 2 and 100 3 are respectively a side elevational view and a plan view of the lever device employed by me for actuating the clutch operating rod; Fig. 4 is a fragmentary view 105 of a detail of construction of the front of the machine; Fig. 5 is a fragmentary plan view of the machine of Fig. 1; Fig. 6 is an

enlarged elevational view similar to Fig. 1, showing the parts in their extreme movement from the position shown in said Fig. 1; Fig. 7 is a fragmentary detailed view showing the mounting of certain of the parts appearing in Fig. 6; Fig. 8 is a still further enlarged view of certain of the parts shown in Fig. 6 illustrating them in the position, however, to which they are restored 10 from that there shown, for the further operation of the machine; Fig. 9 is a view taken from the rear of the machine of certain parts shown in side elevation in Fig. 8; and Fig. 10 is a fragmentary sectional view 15 of certain details of construction, taken centrally and longitudinally of Fig. 8.

Referring first to Fig. 1 of the drawings, it will be noted that for purposes of convenience in illustration as above suggested 20 I have shown a well known type of power punch press wherein a main frame having body portions 11-11, legs 12-12 supports a guide 13 in which is mounted a ram 14 carrying a punch (not shown) for forming 25 material resting in a die (not shown) carried in a base 15, the ram 14 being actuated by means of a link carried on a crank shaft 16 which also carries a fly wheel 17. Power is supplied in any suitable manner to the 30 crank shaft 16, as through the fly wheel 17 and a clutch intermediate said fly wheel 17 and crank shaft 16, which clutch is respectively thrown into and out of operation by lowering and raising the clutch operating or 35 connecting rod 18 which is pivoted at 21 to the frame 11 and is ordinarily movable by means of a treadle (not shown) attached to the treadle rod 22. In machines embodying my present improvements, however, the 40 treadle is ordinarily disconnected from the rod 22 or such rod 22 disconnected from the rod 18, and the primary operating lever 23 is applied in lieu thereof.

The lever 23 as will appear on examination of Figs. 2 and 3 is operable by the right hand of the machine operator and preferably includes a body portion 24 provided with a hook 25 adapted for engagement with the pivot pin 19 or an extension thereof, and an 50 oppositely disposed hook 26 adapted for engagement with the main pivot stud 21, the opposite end of the lever 23 being provided with a push rod 27. The hook 25 is preferably fixed in position on the part 24 in such 55 a manner as to be easily removable therefrom, and the hook 26 is preferably pivotally mounted thereon as indicated at 28 and adapted to be secured in position by means of a screw 29 which may be removed to the 60 end that the hook 26 may be moved to the position indicated in dotted lines in Fig. 2 for the purpose of removal of the lever 23 from the machine.

For the purpose of restraining either accidental or intentional movement of the pri-

mary lever 23 and hence reciprocation of the ram 14, at all times save when the left hand of the operator is removed from the die and actively engaged in depressing of the push rod 30 of the secondary lever 31, I have provided the safety latch mechanism which I will now proceed to describe in connection with Figs. 1, 5 and 6.

On inspection of Fig. 5 it will be noted that the frame members 11, 11, are provided with rearwardly extending ears 32, 32, in which is mounted a rocking counter shaft 33. At one end of the counter shaft 33 is disposed a thimble 34 fixed against rotation thereon, which thimble carries at right angles thereto a sleeve 35 in which the outer end 36 of the lever 31 is disposed and held in position by means of a pin 37. The lever 31 is normally supported in the position shown in Fig. 1 by means of a tension spring 38 engaging a sliding block 39 which may be fixed in position on said lever 31 by means of a set screw 40, the opposite end of such spring 38 being supported at some convenient point on one of the frame members 11 45 as indicated at 41. The end of the shaft 33 opposite to the thimble 34 carries fast against rotation thereon a depending lock arm 42 having a laterally extending catch pin 43 provided with a roller 43^a adapted to engage 50 a hook 44 on a bell crank lever 45 which is pivoted at 46 to a substantially upright lock arm 47 which in turn is pivoted about said main pivot point 21 hereinabove referred to, the said lock arm 47 being provided with a 55 removable bifurcated catch 48 held in position by a screw 49 (see Fig. 6) which normally engages (as shown in Fig. 1) the under side of a cone 50 formed at the upper extremity of a vertically movable rod 51. The rod 51 is pivotally connected to the 60 clutch operating rod 18 at the point 19 above referred to, and is carried in an aperture in a boss 52 formed in the frame 11, a helically coiled spring 53 encircling said rod 51 and 65 normally restrained between said boss 52 and a pair of lock nuts 54 being supplied for the purpose of normally maintaining the rod 51 in the position indicated in Fig. 1. A 70 spring 55 engages the lock arm 47 and said spring 55 is employed for normally holding the catch 48 in contact with the under side of the cone 50 as shown in Fig. 1.

Referring now more particularly to Figs. 6 and 7 it will be observed that for the purpose of lifting the lever 45 to the position shown in Fig. 1, when it is removed therefrom, I employ a coiled compression spring 56 mounted in an extension 56^a of the catch rod 47. To move the arm 45 downwardly 75 so as to bring about the disengagement of the hook 44 and roller 43^a, the pin 57^a is provided which engages the downwardly projecting arm of the lever 45.

Referring now more particularly to Figs. 130

6 to 10 of the drawings, it will be observed that for the purpose of permitting but a single actuation of the machine, that is, in the present case, but a single revolution of the 5 crank shaft 16, I divide the clutch operating rod 18 into upper and lower portions, 18^a and 18^b, respectively, mounting them in apertures bosses 58 and 59 respectively formed on a plate 50 which may be attached to the 10 frame member 11 by screws 61, 61. The member 18^b has fixed in position in its uppermost end by a set screw 62, a clevis 63 having pivotally mounted therein a hook 64 normally adapted to engage a pin 65 carried by the 15 clevis 66 fixed to the rod 18^a by means of a set screw 67. The rod 18^b is normally supported in the raised position shown in Fig. 8 by means of a spring 68 encircling such rod and held under compression between the 20 boss 58 and the sliding block 69 secured to such rod by means of the set screw 70. The hook 64, which as will be seen on inspection of Fig. 8, is pivoted in the clevis 63 as indicated at 71, is normally held in the position 25 shown by means of a tension spring 72, one end of which is fastened to the block 59 as indicated at 73 and the other engages a lever arm 74 formed on said hook and disposed just above the tripping rest 75 provided with 30 an adjusting screw 76, the function of which will be pointed out hereinafter in connection with the description of the operation of the present machine.

In the operation of a punch press of the 35 character above described containing the safety latch for the clutch operating rod thereof embodying my present invention, it will be observed that the operator must depress the push rod 30 by his left hand, thereby 40 moving the lever 31 and rocking the depending arm 42 carried by the counter shaft 33 from the position shown in Fig. 1 to the position shown in Fig. 6. This rocking movement by virtue of the engagement 45 of the roller 43^a carried by the pin 43 and engaging the hook 44 will move the lever 45 to the right or rearwardly of the machine, and by virtue of the pivotal connection indicated at 46 this will move the upright arm 50 47 in the same direction, releasing the bifurcated catch 48 from the cone 50, which will permit the push rod 27 to be depressed by the right hand of the operator, thereby lowering the clutch operating rod 18 (see 55 Fig. 1) and allowing the crank shaft 16 to revolve. When interrupting mechanism, such as is shown in the device of Figs. 6 to 10 is employed, the lowering of the rod 18^b causes the arm 74 to strike the trip rest 75 60 (or the set screw 76, which is provided for the purpose of varying the critical movement of the operation of the trip,) thereby causing the hook 64 to disengage itself from the pin 65, releasing the rod 18^b which is immediately lifted by means of the spring 68 and the

clutch thereby thrown out, and the movement of the crank shaft 16 stopped.

The complete cycle of operation of the machine is now completed, and the levers 23 and 31 must both be returned to their normal 70 positions shown in Fig. 1 before the operation can be repeated for the reason that raising of the lever 31 alone will not cause or permit repetition of the cycle of operation since such lever has no actuating engagement with the rod 18, or either part 18^a or 18^b thereof, and raising of the rod 23 alone followed by redepression thereof will not cause or permit it since such lifting is accomplished by a pushing away of the catch 48 by the cone 50 75 and immediate engagement with the lower surface of such cone 50 by the catch 48, due to the action of the spring 55, which prevents any substantial movement of the lever 23 until the connection is reestablished between the 80 arm 42 and hook 44 and rearward movement of said arm 42 again withdraws the catch 48 from the cone 50. Immediately upon the depression of the rod 51 subsequent upon depression of the rod 23, the latch 48 rides onto 85 the cone 50 by virtue of the action of the spring 55 drawing the upright member 47 to the left or toward the front of the machine and simultaneously carrying the lever 45 in the same direction and causing the hook 44 to 90 abut under the roller 43^a, thus restoring the parts 44 and 48 in position to be reengaged by the parts 43^a and 50 upon the lifting of the levers 31 and 23 respectively.

Obviously as soon as the lever 23 is lifted, 100 the spring 72 tends to retract the hook 64 from the position shown in Fig. 6 to that shown in Fig. 8, which causes the hook 64 to reengage the pin 65 and accomplish the hook and link connection between the parts 105 18^b and 18^a which will remain restored until the rod 18^b is again depressed by depression of the lever 23, as above described.

Having thus described my invention and illustrated its use, what I claim as new and 110 desire to secure by Letters Patent is:

1. In an apparatus of the character described, in combination with means for controlling a power supply, a primary manually operated lever for actuating the controlling means, and a secondary manually operated lever for controlling the operation of said first mentioned lever, both of said levers being arranged to require movement into operative position before said operating means may be actuated and to require restoration to their initial position before said operating means may be again actuated. 115

2. In an apparatus of the character described, in combination with means for controlling a power supply, a primary manually operated lever for actuating the controlling means, and a secondary manually operated lever for controlling the operation of said first mentioned lever, said secondary lever 120

being inoperatively connected to said power controlling means, and a locking device for preventing said primary lever being depressed when said secondary lever is in its 5 inoperative position, said primary lever being inoperative except when said secondary lever is in operative position.

3. In an apparatus of the character described, in combination with means for controlling a power supply, a primary manually operated lever for actuating the controlling means, a secondary manually operated lever for controlling the operation of said first mentioned lever, and an interrupting device for discontinuing the actuating relation between said primary lever and said power controlling means upon completion 10 of the initial movement of said primary lever.

20 4. In an apparatus of the character described, in combination with means for controlling a power supply, a primary manually operated lever for actuating the controlling means, a secondary manually operated 25 lever for controlling the operation of said first mentioned lever, and an interrupting device for discontinuing the actuating relation between said primary lever and said power controlling means upon completion 30 of the initial movement of said primary lever, said levers being arranged for consecutive movement into operative position before said controlling means may be actuated.

35 5. In an apparatus of the character described, in combination with means for controlling a power supply, a primary manually operated lever for actuating the controlling means, a secondary manually operated lever for controlling the operation of said first mentioned lever, and an interrupting device for discontinuing the actuating relation between said primary lever and said power controlling means upon completion 40 of the initial movement of said primary lever, said levers being arranged for consecutive movement into and out of operative position in beginning and repeating the actuation of said power controlling means.

50 6. In an apparatus of the character described, in combination with means for controlling a power supply, a primary manually operated lever for actuating the controlling means, a secondary manually operated lever for controlling the operation of said first mentioned lever, and an interrupting device for discontinuing the actuating relation between said primary lever upon completion of the initial movement of said 55 primary lever and said power controlling means, said secondary lever being arranged to require restoration to normal position before the operation of said primary lever may be repeated.

65 7. In an apparatus of the character de-

scribed, in combination with means for controlling a power supply, a primary manually operated lever for actuating the controlling means, a secondary manually operated lever for controlling the operation of 70 said first mentioned lever, and an interrupting device for discontinuing the actuating relation between said primary lever and said power controlling means, upon completion of the initial movement of said primary 75 lever, said primary lever being inoperative except when said secondary lever is in operative position and said secondary lever being arranged to require alternative restoration to inoperative position and movement 80 therefrom before said first mentioned lever may be again operated.

8. In an apparatus of the character described, in combination with means for controlling a power supply, a primary manually operated lever for actuating the controlling means, a secondary manually operated lever for controlling the operation of said first mentioned lever, and an interrupting device for discontinuing the actuating relation between said primary lever upon completion 85 of the initial movement of said primary lever, said secondary lever being inoperatively connected to said power controlling means, and said primary lever being inoperative except when said secondary lever is in operative position.

9. In an apparatus of the character described, in combination with a main frame and means for controlling a power supply 100 supported thereby, a primary manually operated lever for actuating the controlling means engaging said means and pivotally mounted on the frame, a resiliently supported lock engaging said lever and means, an upright arm pivoted about said pivot point and provided with a catch resiliently 105 engaging said lock, a rock shaft carried by the frame, a resiliently supported secondary lever and a rocker arm mounted on said shaft, and a resiliently held lever provided with a hook engaging said rocker arm and pivoted to said upright arm.

10. In an apparatus of the character described, in combination with means for controlling a power supply, a primary manually operated lever for actuating the controlling means permanently connected thereto, and a secondary manually operated lever for controlling the operation of said first-mentioned lever, both said levers being arranged to require consecutive movement into operative position before said operating means may be actuated.

11. In an apparatus of the character described, in combination with means for controlling a power supply, a primary manually operated lever for actuating the controlling means, and a secondary manually operated lever for controlling the operation 125

130

of said first-mentioned lever, said primary lever requiring the movement of said secondary lever before it can be moved.

12. In an apparatus of the character described, in combination with means for controlling a power supply, a primary manually operated lever for actuating the controlling means, controlling means permanently connected thereto, and a secondary

10 manually operated lever for controlling the operation of said first-mentioned lever, said primary lever requiring the movement of said secondary lever before it can be moved.

13. In an apparatus of the character described, in combination with means for controlling a power supply, a primary manually operated lever for actuating the controlling means, a secondary manually operated lever arranged to require alternate 20 movement relatively to the primary lever for controlling the operation of said first-mentioned lever, and a member adapted to prevent the operation of said lever except when moved out of engagement therewith 25 by said secondary lever.

14. In an apparatus of the character described, in combination with means for controlling a power supply, a primary manually operated lever for actuating the controlling means, and a secondary manually operated lever arranged to require alternate 30

movement relatively to the primary lever for controlling the operation of said first-mentioned lever, a member adapted to prevent the operation of said lever except when moved out of engagement therewith by said secondary lever, and means operated by said primary lever for restoring said member to engaging position after the operation of said primary lever.

15. In an apparatus of the character described, in combination with means for controlling a power supply, a primary manually-operated lever for actuating the controlling means arranged adjacent one side 40 of the apparatus substantially parallel thereto, and a second manually-operated lever for controlling the operation of said first-mentioned lever arranged adjacent the opposite side of said apparatus and substantially parallel thereto, both said levers being arranged to require consecutive movement into operative position before said operating means may be actuated.

In testimony whereof I have hereunto 55 signed my name in the presence of the two subscribed witnesses.

OSCAR L. SCALBOM.
